UNITED STATES PATENT OFFICE.

GEORGE J. GOODHUE, OF STEVENS POINT, ASSIGNOR OF ONE-HALF TO
HARVEY M. WADLEIGH, OF HATLEY, WISCONSIN.

WOOD-WORKING MACHINE.

SPECIFICATION forming part of Letters Patent No. 374,670, dated December 13, 1887.

Application filed May 2, 1887. Serial No. 236,829. (No model.)

To all whom it may concern:

Be it known that I, GEORGE J. GOODHUE, of Stevens Point, in the county of Portage, and in the State of Wisconsin, have invented 5 certain new and useful Improvements in Wood-Working Machines; and I do hereby declare that the following is a full, clear, and exact description thereof.

My invention relates to wood-working machines, being specially designed for shaping the ends of the legs that form part of the timber structure for mines, set forth in Letters Patent No. 358,261, dated February 22, 1887; and it consists in certain peculiarities of construction and combination of parts, to be hereinafter described with reference to the accompanying drawings, and subsequently claimed.

In the drawings, Figure 1 represents a perspective view of a machine constructed according to my invention; Figs. 2 and 3, elevations of a cutter-head employed in the machine, and Fig. 4 an elevation showing the product of said machine.

Referring by letter to the drawings, A represents the mill-floor; B, a platform raised above the same, and C a chute, that preferably comprises an inclined frame having a series of rollers journaled therein.

Preferably pivoted to the platform B are 30 short skid-sections D, arranged to be brought over the chute C and rest on long skid-sections E, pivotally secured to said chute and extended forward over a chuck-frame, F, the latter being mounted on movable beams F' F''. The forward ends of the skid-sections E are 35 connected by rods G with hand-levers H, that are in turn suspended from the ceiling of the mill-room or other suitable support by rods I, and said levers are individually retained in 40 any position to which they may be adjusted by means of rack-bars J.

The movable beams F'', that aid in supporting the chuck-frame, have mounted thereon racks K, to engage pinions L' on a horizontal 45 shaft, L, the latter having its bearings in boxes M' on beams M, rigidly secured to the mill-floor. One end of the shaft L carries a gear-wheel, N, that meshes with a pinion, O', on the adjacent end of a vertical shaft, O, the 50 latter being journaled in a suitable frame-

work, P, and is provided at its other end with a hand-wheel, O''. The skid-sections D being let down over the chute C, the timber to be operated upon is rolled from the platform B onto the skids E to position between the 55 chucks Q R, that have their spindles Q' R' mounted in suitable bearings on the frame F. By operating the levers H the timber is raised or lowered to get it centered with the chucks Q R, and when this centering has been accomplished the spindle of the latter chuck is moved inward by means of the screw-rod R'' and hand-wheel R'', for the purpose of causing both of these chucks to enter the respective ends of said timber. The chuck Q is fast on 65 its spindle, while the one, R, runs loose. A gear-wheel, S, is secured to the outer end of the chuck-spindle Q', to be engaged by a pinion, S', on a shaft, S'', that is journaled in the frame F and carries a belt-pulley, S''. Power 70 being applied to the chuck-spindle Q', through the medium of the gear just described, the timber is slowly revolved, and when the hand-wheel O'' is operated motion is transmitted to the shaft L by means of the pinion O' and 75 gear-wheel N, thereby causing the pinions L' to exert their power on the racks K to actuate the carriage, comprising the chuck-frame F and movable beams F' F''. As the carriage is moved forward, the ends of the timber chucked 80 therein come into contact with cutter-heads T, fast on shafts U, journaled in boxes V, that are secured to vertical posts W. Each shaft is provided with a drive-pulley, X, and can be moved in or out to adjust the cutter-heads T 85 to different lengths of timber, said shafts being retained in their adjusted position by set-collars X'.

Each of the cutter-heads T comprises a cylindrical shell closed at one end and having its 90 outer periphery provided with a series of longitudinal seats, a, to which are adjustably secured detachable knives b, and said closed end of the shell has a series of radial seats, c, for adjustable saws d, the latter being preferably double-ended, and also detachable from their seats.

Forming part of or removably secured to the shell above described is another shell, T', of less diameter, but like the former shell, 100

is provided on its outer periphery with longitudinal seats *e*, to which are adjustably secured detachable knives *f*, and the closed end of this latter shell has two or more radial seats, *g*, for 5 detachably-connected adjustable saws *h*. The shafts carrying the cutter-heads *T* are driven at a comparatively high rate of speed, and the timber on the carriage is first brought into contact with the saws *d*, said saws being slightly 10 in advance of the knives *b*. The saws *d* make a circular cut in the timber, and being followed up by the knives *b* the ends of said timber are gradually chipped away to leave a round 15 gudgeon, *i*, as shown by Fig. 4, the movement of the carriage being limited by a stop or stops, *Y*. Before the saws *d* and knives *b* on the larger shells of the cutter-heads have finished their work the saws *h* and knives *f* on the smaller shells, *T'*, come into play against 20 the timber to, in the same manner, cut away enough of said timber to form circular shoulders *j*, adjacent to the gudgeons *i*, one of such shoulders being also shown in Fig. 4.

While I prefer to make a shoulder, *j*, on 25 both ends of the timber, the smaller shells, *T'*, carrying the saws *h* and knives *f*, may be omitted from either one or both of the cutter-heads.

When the cutting has been completed, the 30 carriage is moved back clear of the cutter-heads, and the timber being released from the chucks is rolled along the skid-sections *E* to the inclined chute *C* and slides down to the point of delivery.

Having thus fully described my invention, 35 what I claim as new, and desire to secure by Letters Patent, is—

1. In a wood-working machine, a revolute cutter-head that comprises two shells of different diameters individually provided with 40 radial saws and longitudinal knives, all the knives on each shell being set at the same angle and at the same distance from the axis of the cutter-head, substantially as set forth.

2. In a wood-working machine, a revolute cutter-head that comprises two shells of different diameters, radial saws detachably connected to a closed end of each shell and adjustable thereon, and longitudinal knives 45 detachably connected to and adjustable on the outer peripheries of said shells, all the knives on each shell being set at the same angle and at the same distance from the axis of the cutter-head, substantially as and for the purpose 50 set forth.

3. In a wood-working machine, the combination of a reciprocative frame provided with revolute chucks and revolute heads, each of which comprises two shells of different diameters individually provided with radial saws and longitudinal knives, substantially as set forth. 60

4. In a wood-working machine, the combination of a reciprocative frame carrying revolute chucks, revolute heads carrying radial saws and longitudinal knives, skids extended over the chuck-frame beyond the cutter-heads, and suitable means for independently adjusting each skid, substantially as and for the purpose set forth. 65

5. In a wood-working machine, the combination of a reciprocative frame carrying revolute chucks, revolute heads carrying radial saws and longitudinal knives, skids extended over the chuck-frame beyond the cutter-heads, a lever mechanism for independently adjusting each skid, and suitable means for retaining said skids in their adjusted position, substantially as and for the purpose set forth. 70

6. In a wood-working machine, the combination of a reciprocative frame carrying revolute chucks, revolute heads carrying radial saws and longitudinal knives, a platform having skid-sections pivotally connected 75 thereto, a chute arranged adjacent to the platform, skid-sections extending from the chute over the chuck-frame beyond the cutter-heads, hand-levers having a rod-connection with each of the latter skid-sections, and rack-bars arranged to engage the levers, substantially as 80 and for the purpose set forth.

7. In a wood-working machine, the combination of a reciprocative frame provided with revolute chucks, laterally-adjustable 95 shafts, a head mounted on each shaft and provided with radial saws and longitudinal knives, suitable means for imparting motion to said shafts, and independently-adjustable skids extended over said frame beyond the cutter-heads, substantially as set forth. 100

In testimony that I claim the foregoing I have hereunto set my hand, at Milwaukee, in the county of Milwaukee and State of Wisconsin, in the presence of two witnesses.

GEORGE J. GOODHUE.
